UNITED STATES PATENT OFFICE.

HERBERT HILTON, OF NEW BEDFORD, MASSACHUSETTS.

POLISH FOR AUTOMOBILES.

1,331,260.

Specification of Letters Patent. Patented Feb. 17, 1920.

No Drawing.

Application filed September 30, 1919. Serial No. 327,425.

To all whom it may concern:

Be it known that I, HERBERT HILTON, a citizen of the United States, residing at New Bedford, in the county of Bristol and State of Massachusetts, have invented certain new and useful Improvements in Polish for Automobiles, of which the following is a specification.

My invention relates to an improved polish for automobiles.

This polish consists of the following ingredients and proportions, to wit:—

Five (5) gallons refined lubricating oil;

Six (6) ounces varnish oak tan;

15 Three-fourths ($\frac{3}{4}$) gallon gasoline.

These ingredients are mixed together, and when the mixture is completed, it cleans, renews, retains and adds a gloss to polished

and enameled surfaces, it being strictly prepared for automobiles, carriages, and kindred accessories, although not especially intended for furniture or other inside or outside wooden articles.

This composition creates a gloss in the form of a light film of varnish.

This improved gloss is non-inflammable; dries immediately; requires no rubbing whatever, but cleans, renews, retains and adds a gloss.

I claim:

30 A gloss or polish for automobiles and the like composed of refined lubricating oil, varnish (oak tan) and gasoline mixed in substantially the proportions set forth.

35 In testimony whereof I affix my signature.

HERBERT HILTON.
